LAMP HOLDER

James F. Beal, Bridgeport, Conn., assignor to The
Bryant Electric Company, Bridgeport, Conn.,
a corporation of Connecticut

Application January 28, 1942, Serial No. 428,482

11 Claims. (CL 173—328)

My invention relates, generally, to lamp holders and, more particularly, to lamp holders for use with double-ended elongated discharge devices, such as a fluorescent lamp, which is supported at each end by a lamp holder and, particularly, lamps of this character which have oval or elliptical envelopes.

The object of my invention, generally stated, is to provide a lamp holder of the character described which shall be of rugged and simple construction and which may be economically manufactured.

A more specific object of my invention is to provide a lamp holder adapted for use with double-ended discharge lamps of the oval or elliptical type having pairs of contact pins at each end located in a plane at 45 degrees with respect to either the major or minor axis of the envelope of the device or lamp.

Another object of my invention is to provide a lamp holder for use with lamps of the character described so constructed that the lamp may be inserted into the holders so that the broad or narrow side of the envelope may be specifically positioned with respect to a reflecting or supporting surface without turning the lamp end-for-end and which may be also used with lamps having a cylindrical envelope.

A still further object is to provide a lamp holder of the character described wherein the lamp may be readily inserted and specifically positioned in one of two positions by simply rotating the lamp in one direction or the other into a locking position.

These and other objects of my invention will become more apparent from the following detailed description when read in conjunction with the drawing, in which:

Figure 1 is a front view in elevation of a lamp holder embodying the principal features of my invention;

Fig. 2 is a top view of the lamp holder of Fig. 1;

Fig. 3 is a view along line III—III of Fig. 1;

Fig. 4 is a view taken along line IV—IV of Fig. 3;

Fig. 5 is a view in front elevation of a modification of the invention;

Fig. 6 is a bottom plan view of Fig. 1 or Fig. 5;

Fig. 7 is a view along line VII—VII of Fig. 5; and

Fig. 8 is a view taken along line VIII—VIII of Fig. 7.

In practicing my invention in its preferred form, a housing comprising a hollow body por-

tion of molded material and open at one side is attached to a metal mounting bracket having a foot portion disposed at right angles to an upright mounting portion which closes the open side of the body portion. The front face of the body portion is provided with a narrow entry slot at the top to receive the contact pins of the lamp. This slot extends downwardly and is enlarged in width and terminates in an inverted Y at the bottom, the Y-portions being relatively deep and narrow. Directly opposite each of the Y-portions and at the upper end of the enlarged portion of the slot there extends in an upward direction, a relatively shallow and narrow portion. Within the body portion there are mounted a pair of resilient contact members or brushes having free end portions which extend upwardly along the outside of the enlarged portion of the slot in slightly overlapping relation with the ends of the Y-portions and the shallow portions opposite thereto. The pins of the lamp enter the slot one above the other, and when the leading pin engages the lower edge of the enlarged portion of the slot, it may be guided into either one of the Y-portions by simply turning the lamp. When the lamp is pushed down into the Y-portion, the leading pin engages the contact member and the lamp may be locked within the opposite shallow portion by turning it so that the trailing or upper pin is in a position to enter the shallow portion of the slot opposite the Y-portion. When the downward force on the lamp is released, the contact member forces it upwardly to cause the trailing pin to become firmly seated in the shallow portion of the slot against the upper end of the other contact member.

The narrow portions, which may be referred to as locking portions, are disposed opposite the Y or guiding portions, and each guiding portion and its opposite locking portion lie in a common plane at 45 degrees to the longitudinal axis of the holder. The two planes in which the pairs of guiding and locking portions lie are disposed in an X formation each at 45 degrees to the longitudinal axis of the holder.

With reference to Figs. 1 to 4 of the drawing, which illustrate a preferred embodiment of the invention, the holder shown comprises a housing formed of an L-shaped metal mounted bracket 10 having a base or foot portion 11 and a flat upright supporting portion 12 to which is attached a hollow open-sided body portion 13 by means of a screw 14. A back plate and liner 8 is interposed between the housing and bracket as shown.

The body portion 13 is preferably molded of a suitable material and is provided with a slot 15 in the top and front face thereof for receiving the contact pins 16 and 17 of the lamp, as best shown in Fig. 1. The slot 15 starts at the top as a relatively narrow entrance portion 18 and extends downwardly into a wider enlarged portion 19 and terminates in downwardly extending Y-portions 20 and 21 which are relatively deep and narrow, and which may be referred to as the guiding portions of the slot. Opposite each Y-portion, at the top of the enlarged portion 19 there are provided narrow and relatively shallow upwardly extending portions 22 and 23, also in Y-formation, and which may be referred to as the locking portions of the slot.

The internal construction of the body portion is best shown in Fig. 4. A rib portion 24 integral with the face of the body portion divides it longitudinally into recesses 25 and 26 in which the resilient contact elements 27 and 28 are mounted. The upper end 29 of the rib is in the shape of an inverted V and functions as a guide for the leading contact pin of the lamp so that it may be pushed into either one of the Y-portions of the slot.

The contact members 27 and 28 may be of any suitable construction and, as shown in this instance, are shaped roughly in the form of a figure 2. They may be constructed of flat spring material having suitable current conducting qualities.

With reference to contact member 27, which is identical to 28, it will be observed that it is formed by bending one end of the strip at an angle to form a terminal portion 31 and curving or bowing the other end of the strip to form a contact portion 32, these two portions being joined together by a straight shank portion 33. The contact members are mounted within the housing by means of transverse slots 34 and 35 formed in the sides of the rib portion 24 and the transverse shoulders 36 and 37 and bosses 38 and 39 formed on the inside of the body portion, as shown. It will be observed that the terminal portion 31 of the contact member 27 is mounted within the slot 34 and rests upon the shoulder 36, the shank portion 33 extending between the inside of the body portion and boss 38 thus functioning to retain the free end of the contact member in proper relation to the guiding and locking portions of the slot 15. A supporting plate 40 may be positioned within the slot 34 in order to retain the terminal portion 31 therein and also function as a nut for the terminal screw. The other contact member 28 is mounted in the same manner.

In order to provide a holder in which a lamp of the oval type may be inserted so as to present either the broad or narrow side of the envelope to a reflecting surface without turning the lamp end-for-end, the guiding and locking portions of the slot 15 are so positioned with respect to the longitudinal axis of the housing as to hold the lamp in either of these two positions.

It will be observed that the guiding portion 20 and the locking portion 23 are positioned opposite each other and in a common plane extending at an angle of approximately 45 degrees to the longitudinal axis of the housing. Likewise, the guiding portion 21 and locking portion 22 are located in a common plane at right angles to the other plane and also at an angle of 45 degrees to the longitudinal axis of the housing. Thus, it is seen that the slot 15 ter-

minates in an enlarged star-shaped portion having radially extending arms formed by the guiding and locking portions.

As shown in Fig. 1, the free ends of the contact members 27 and 28 extend upwardly in overlapping relation to the ends of the guiding and locking portions of the slot in order that they may be engaged by the contact pins of the lamp. The initial or disengaged position is indicated by the dotted outline designated *a*.

The initial position of the contact pins is shown in Fig. 1 by the dotted outline. It will be noted that the leading pin 16 is resting upon the upper end 29 of the rib 24 where it is in a position to enter either of the guiding portions 20 and 21. The trailing pin 17 is in the entrance portion 18 of the slot and acts as a pivot point for the lamp.

If it is desired to insert the lamp with its major axis at right angles to the longitudinal axis of the housing so that the envelope is in the position as shown by the dash-dot outline, the lamp is rotated in a clockwise direction, so that the pin 16 follows the guiding portion 20 to the bottom as shown. In this position, it has engaged contact member 27 and the trailing pin 17 has reached the bottom of the entrance portion 18 of the slot, where it is in a position to enter the opposite locking portion 23. The reaction of the contact member 27 against the leading pin 16 urges the trailing pin 17 into the locking portion 23 against the other contact member 28. The final position of the contact pins is as shown by the cross-hatched section.

In the event that it is desired to insert the lamp in its other position, as shown by the dashed outline thereof, the leading contact pin 16 is guided into the other guiding portion 21 into engagement with contact member 28, and the trailing pin 17 is forced into the other locking portion 22 where it engages the contact member 27.

In view of the foregoing description, it will be apparent that by means of the use of a slot of this shape, a double-ended discharge lamp of the oval type may be inserted into the holder in either of its two positions without turning the lamp end-to-end, as is required when lamp holders of the conventional type are used. It will also be apparent that the lamp holder described may be used with lamps of the ordinary round type.

The modification shown in Figs. 5 through 8 is substantially the same except that the contact members thereof are of a different shape. As shown in Fig. 5, for example, the contact members 41 and 42 are hook-shaped and have long shank portions 43 and 44 extending upwardly from their terminal portions 45 and 46. The free ends 47 and 48 are bent inwardly to form the hook and extend downwardly in overlapping relation with the ends of the guiding and locking portions of the slot 18. The tips of the free ends are also hook-shaped to receive the contact pin, as shown. In this instance, the leading pin 16 is received by the hook-shaped end of the contact member 41 and urges the trailing pin 17 into the locking portion 23 in engagement with the contact member 42. The contact members 41 and 42 are mounted within the housing in generally the same manner as described in connection with the preferred embodiment of the invention and the initial or disengaged position of the contact members is indicated by the dotted outline designated *a* in Fig. 5.

In view of the foregoing, it will be apparent that I have provided a lamp holder of simple and rugged construction adapted for use with double-ended discharge lamps of the oval type, and so constructed that these lamps may be inserted into the holder in either of their two operating positions without turning the lamp end-to-end.

Since the illustrated examples constitute only two practical embodiments of my invention, I do not wish to limit myself strictly to the exact details illustrated, since modifications of the same may be made without departing from the spirit of the invention as defined in the appended claims.

I claim as my invention:

1. A lamp holder for use with double-ended electric lamps having a tubular envelope and pairs of spaced contact pins at each end thereof comprising, a hollow housing member having a base portion for mounting it on a supporting surface, a pair of resilient contact members mounted within the housing, said housing having a slot in one face thereof adjacent the contact members for receiving the contact pins of the lamp, said slot having a plurality of pairs of opposed guiding and locking portions, each pair of guiding and locking portions of the slot being disposed in a common plane positioned at a predetermined angle to the longitudinal axis of the housing, whereby the lamp may be inserted into the holder in a plurality of positions to selectively position the envelope without turning the lamp end-for-end.

2. A lamp holder for use with double-ended electric lamps having a tubular envelope and a pair of spaced contact pins at each end thereof comprising, a hollow housing member having a base portion for mounting it upon a supporting surface and a flat face portion, said housing having a slot in the flat face portion extending downwardly from the top thereof, said slot having a narrow-entrance portion and radially extending guiding and locking portions at the lower end thereof, each of said locking portions being disposed opposite a guiding portion in a plane extending at a predetermined angle to the longitudinal axis of the housing, a pair of resilient contact members mounted within the housing, said contact members being rigidly attached to the housing at one end only and having their free ends extending upwardly in overlapping relation to the ends of the guiding and locking portions of the slot in such position as to be engaged by the contact pins of the lamp when inserted into said guiding and locking portions.

3. A lamp holder for use with double-ended electric lamps having a tubular envelope and a pair of spaced contact pins at each end thereof comprising, a hollow housing member having a base portion for mounting it upon a supporting surface and a flat face portion, said housing having a slot in the flat face portion extending downwardly from the top thereof, said slot having a narrow entrance portion and radially extending guiding and locking portions at the lower end thereof, each of said locking portions being disposed opposite a guiding portion in a plane extending at a predetermined angle to the longitudinal axis of the housing, a pair of elongated resilient contact members mounted within the housing and attached thereto at one end only with their free ends extending upwardly adjacent said slot, said free ends of the contact members being curved inwardly to overlap the edges of the guiding and locking portions of the slot

so as to be engaged by the contact pins and resiliently urge said pins into locking position within the slot.

4. A lamp holder for use with double-ended electric lamps having a tubular envelope and a pair of spaced contact pins at each end thereof comprising, a hollow housing member having a base portion for mounting it upon a supporting surface and a flat face portion, said housing having a slot in the flat face portion extending downwardly from the top thereof, said slot having a narrow entrance portion and radially extending guiding and locking portions at the lower end thereof, each of said locking portions being disposed opposite a guiding portion in a plane extending at a predetermined angle to the longitudinal axis of the housing, a pair of resilient contact members mounted within the housing and attached thereto at one end only, said contact members being hook-shaped having their ends extending downwardly in overlapping relation to the ends of the guiding and locking portions of the slot, whereby when the contact pins are inserted into the slot the leading pin follows one of the guiding portions into engagement with the end of one contact member which exerts an upward force to cause the trailing contact pin to be held within the opposite locking portion of the slot against the other contact member.

5. A lamp holder for use with double-ended electric lamps having a pair of spaced contact pins extending from each end thereof comprising, a body portion of insulating material having a pair of longitudinally extending recesses, a bracket member for supporting the body portion in an upright position, a pair of resilient contact members mounted within said recesses, said body portion having an inverted Y-shaped slot in one face thereof to receive the contact pins of the lamp, said slot having locking portions intermediate the ends thereof opposite the lower leg portions of the Y, whereby the contact pins may be positioned in either leg of the Y and the opposed locking portions in engagement with the contact members.

6. A lamp holder for use with double-ended electric lamps having a pair of spaced contact pins extending from each end comprising, a housing formed at least in part of insulating material and having a mounting base, said housing being of hollow construction and having a slot in one face thereof for guiding and holding the contact pins, and a pair of contact members mounted therein for engagement by the contact pins of the lamp, said slot having an entrance portion extending from the top of the housing downwardly into an enlarged portion having deep downwardly extending narrow portions and opposed shallow upwardly extending narrow portions, each deep portion being in the same plane as its opposed shallow portion at a predetermined angle to the longitudinal axis of the housing.

7. A lamp holder for use with double-ended electric lamps having an oval envelope and a pair of spaced contact pins extending from each end thereof comprising, a housing formed at least in part of insulating material and having a mounting base, said housing being of hollow construction and having a slot in one face thereof, and a pair of contact members mounted therein for engagement by the contact pins of the lamp, said housing having a slot in one face thereof for guiding and holding the contact pins, said slot having a narrow entrance portion extending

downwardly from the top of the body portion into an enlarged portion having narrow relatively deep downwardly extending portions at the bottom in Y formation and disposed at 45 degrees to the longitudinal axis of the body portion and relatively shallow locking portions at the top opposite to and lying in the same plane with the relatively deep portions, whereby the lamp may be mounted within the socket with either the major or minor axis of its envelope along the 10 longitudinal axis of the body portion.

8. A lamp holder for use with double-ended electric lamps of the oval type having pairs of spaced contact pins at each end located in a common plane at 45 degrees to the minor and major axes thereof comprising, a hollow body portion of insulating material having a slot in the face thereof to receive the contact pins and a pair of resilient contact elements mounted therein, said slot having a straight entrance portion extending downwardly from the top of the body portion and terminating in an enlarged portion having two pairs of upper and lower extensions lying in crossed planes at 45 degrees to the longitudinal axis of the body portion, whereby the contact pins of the lamp may be positioned within either pair of extensions to specifically position the lamp without turning it end for end.

9. A lamp holder for electric lamps of the double-ended type having pairs of spaced contact pins at each end thereof comprising, an L-shaped mounting bracket having a flat upright portion, a hollow body portion of insulating material attached to one side of the upright portion of the bracket, said body portion having a slot in the face thereof to receive the contact pins of the lamp, said slot being open at the top and terminating in two pairs of oppositely disposed portions lying in crossed planes at 45 degrees to the longitudinal axis of the body portion, and re- 40

5 silent contact members mounted within the body portion adjacent said oppositely disposed portions of the slot, whereby the lamp may be inserted into the holder and partially rotated in either direction into locking position with its contact pins in engagement with the contact members.

10. A lamp holder for use with a double-ended lamp having pairs of spaced contact pins at each end thereof comprising, a hollow housing member provided with a slot in one face thereof to receive the contact pins of the lamp, said slot having a vertical portion extending from the top of said hollow member and terminating in an enlarged portion with narrow extended portions disposed opposite each other at an angle of 45 degrees to the longitudinal axis of the hollow housing member, and contact members mounted within the hollow member disposed to be engaged by the contact pins of the lamp when inserted 15 into the slot and rotated in either direction to cause the pins to enter either one of the pairs of extended portions of the slot.

11. A lamp holder for use with a double-ended lamp having pairs of spaced contact pins at each end thereof comprising, a hollow member provided with a slot in one face thereof to receive the contact pins of the lamp, said slot having a vertical portion extending from the top of said hollow member and terminating in an enlarged 20 X-shaped portion having oppositely disposed upwardly and downwardly extending narrow portions positioned in crossed planes at 45 degrees to the longitudinal axis of the member, and a pair of resilient contact members mounted within the 25 hollow member adjacent said X-shaped portion of the slot to be engaged by the contact pins when inserted into the slot and rotated into the upwardly and downwardly extending narrow portions thereof.

JAMES F. BEAL.
